ROTARY TYPE SELECTOR SWITCH FOR
AUTOMATIC TELEPHONE SYSTEMS

Douglas Percy Long, Chislehurst, England, assignor to Siemens Brothers & Co. Limited, London, England, a British company

Application January 10, 1946, Serial No. 640,260
In Great Britain January 1, 1945

9 Claims. (Cl. 179—18)

1

This invention relates to automatic telephone systems and more particularly to the control of selecting switches required to search in a group of outlets in accordance with a marking applied to their contact banks consequent on the receipt of a train of impulses. It has in view improved means for the control of a single motion selecting switch by apparatus individual to the switch and using the minimum of control apparatus.

In a single motion selecting switch having a large number of outlets wiper switching may be employed whereby the switch is constrained to search in one or other of two sets of banks. As the time available for searching is limited by what is known as the inter-train pause the number of consecutive bank contacts which can be tested within that period of time is dependent on the speed of operation of the switch. Owing to this limitation and the necessity for avoiding complicated or uneconomical wiper switching arrangements, arrangements have been proposed in which an increase in the number of outlets may be had by adapting the wipers to sweep two banks in succession, hereinafter termed a pair, and for search in the second of the two banks a preliminary setting is given to the wipers at the time the selecting switch is taken into use.

This may be effected dependent on the path of entry to the selecting switch or other discriminating action such as a signal from a preceding switching stage. The selecting switch may be taken into use in response to either of a pair of digital values received at a preceding switching stage, the discriminating action serving to distinguish between the two digital values of the pair. Outlets corresponding to one such value would then be accommodated in one of the two banks of the pair and outlets corresponding to the other of such digital values would be accommodated in the other of the said two banks. In addition, a further discriminating action may be had by wiper switching in accordance with the digital value actually received at the selecting switch.

In the present invention it is arranged that the stopping circuit for the selecting switch is dependent on the condition of the dialling relay which is usually provided to determine the end of an impulse train. In one condition of this relay the selecting switch may move to take up a preliminary position adjacent to a set of outlet groups in response to a discrimination effected at the time the switch is taken into use and in the other condition of the relay the selecting switch performs its searching function for a free outlet in a marked group. During the preliminary setting

5

impulses may be received in the switch circuit and in accordance with the usual practice the dialling relay is operated prior to receipt of the switch setting train. In its operated condition the dialling relay connects the test relay in a circuit in which the operation of the latter depends on a wiper reaching the contact in the selecting switch bank at the desired preliminary position. The selecting switch has therefore to move to its preliminary position before the dialling relay releases at the end of the impulse train. This is ensured without imposing limitations on the disposition of the outlets by employing a high speed selecting switch and a dialling relay with a release lag long enough to extend over the preliminary setting period even if only a single impulse has been received. In the other condition of the dialling relay the test relay should be connected to the test wipers in the normal manner.

10 20 The discriminating action is conveniently effected by a relay which is operated or not at the time the selecting switch is taken into use and which, in one condition initiates the preliminary movement of the selecting switch. A suitable relay for the purpose is the wiper switching relay and it is convenient that the operation of this relay at the time of seizure of the selecting switch should initiate the preliminary movement. It may be arranged that after such operation it is re-

15 30 leased prior to the time at which its operation may be required for wiper switching purposes, the circuit for the continued driving of the selecting switch being maintained by other means after the release of the wiper switching relay. The discriminating action may be brought about by means of a signal from a preceding circuit. The signal may conveniently take the form of an absence of potential on one of the line wires at the time of switching through whereby the relay is allowed to operate in a loop circuit to initiate the preliminary movement of the selecting switch. On the other hand, if no signal is to be transmitted a suitable potential is applied to the said line wire to prevent operation of the relay.

40 45 50 55 While the contacts in the selecting switch bank on which the switch is to stop in its preliminary movement may be marked directly the outlets to be searched will be marked in a circuit including a contact of a marking device and a back contact of the dialling relay. The marking device may take the form of a stepping switch responsive to digits and suitably connected contacts may serve for the operation of the wiper switching relay for wiper switching purposes. In conjunction with mid-normal contacts on the selecting switch

one or other of two wipers of the stepping switch may be connected up and their associated contacts connected as required to the wiper switching relay. Under these operating conditions a locking circuit for the wiper switching relay would be provided. Other mid-normal contacts of the selecting switch may be used for similar differentiation for other purposes, such as the operation of overflow meters. The mid-normal contacts referred to are contacts operated when the selecting switch wipers reach the mid-normal or preliminary contact position and restored when the wipers have passed over the bank and reached their normal position.

It may also be arranged for the dialling relay to operate over a last contact in any of the banks in series with the test relay so that with the dialling relay and the switching relay being in an operated condition at the same time the transmission of a busy signal may be brought about. For this purpose the dialling relay is preferably made somewhat slow in operating in order to ensure the prior operation of the switching relay.

The invention is illustrated by way of example in the accompanying drawing. The drawing shows circuits for a 200 outlet motor uniselector of the general type described in U. S. Patent No. 1,956,371 to David Adam Christian acting as a group selector. The selector has 8 wipers, each comprising a pair of electrically connected wipers displaced axially along the switch shaft and adapted to engage arcs of 52 contacts each in succession. The set of wipers shown in full lines are the first wipers of the pairs to enter the bank and make contact in the arcs shown by full lines and the second wipers of the pair to enter the bank are shown in dotted lines and make contact with the dotted line arcs. The first wipers of the pair and their associated arcs are herein referred to as the W and Y wipers and arcs and the second wipers of the pair and their associated arcs are herein referred to as the X and Z wipers and arcs. The outlets form two main groups, one connected to the W and Y arcs and the other to the X and Z arcs and are reached in response to one or other of a pair of digits received at the preceding selecting switch. The W and X wipers are accessible over back contacts of wiper switching relay WS and the Y and Z wipers are accessible over front contacts of relay WS. Selection between the two sets connected over the back and front contacts of relay WS is performed in accordance with the digit received at the selector shown in the drawing, and selection between the two wipers of a pair, (WX or YZ), is effected by a discriminating action at the time the selector is taken into use to determine in which of the two main groups selection by the selector in response to a received digit is to be effected. In the example taken this discriminating action is performed on receipt of a discriminating signal the effect of which is to cause the selector to execute a preliminary movement whereby the W and Y wipers are rotated over their arcs and the X and Z wipers are brought to a position in which contact is made with the first contacts in the dotted arcs and search is subsequently made in the X and Z portions of the bank. If no signal is received search takes place in the W and Y portions of the bank represented by the full line arcs. The wipers are driven by an electric motor represented by the magnet MU and off-normal contacts ON1 and ON2 are provided which are operated when the W and Y wipers leave their

normal position and remain operated while all the wipers are off-normal. Mid-normal contacts MN1 and MN2 are also provided and these are operated when the X and Z wipers reach the first contacts in the dotted arcs and remain operated so long as the X and Z wipers are in the bank. Associated with the selector is a digit switch which is stepped by the impulses of the received digit to mark the contact group in the selector in which search is to be made as determined by the impulses received. The digit switch is driven by the magnet DM and has 7 wipers. Of these, wipers M1 and M2 are marking wipers, wiper M1 being used for marking in the W and Y arcs and wiper M2 for marking in the X and Z arcs. The banks of wipers M3 and M4 are cross connected as required for the operation of relay WS by a received digit requiring wiper switching and provide for different markings, if need be, for the same digital value in the two main groups of outlets and the arcs of wipers M5 and M6 are similarly connected to overflow meters. Wiper M7 serves for providing for the transmission of a discriminating signal in the case in which outlet groups are common to two digits. It also provides a circuit for the initial operation of relay WS to bring about the preliminary movement of the selector above referred to. The digit switch has an armature operated contact dm and off-normal contacts DON1 and DON2. The relays shown are the impulse receiving relay A, release relay B, dialling relay C, test relay T, switching relay H and wiper switching relay WS. Of these relays, relay B is slow to release, relay C is slow to operate and release and relay T is a high speed relay.

The selector is adapted to be taken into use by either of a pair of digits received at the preceding switching stage. If the digit received is odd a discriminating signal is transmitted and relay WS is operated to initiate the preliminary movement of the selector which is executed before, and may be, during the reception of the selecting impulses and selection takes place in the XZ sections of the bank while if the digit is even a discriminating signal is not transmitted and no preliminary movement takes place and selection takes place in the WY sections of the bank or vice versa. Similarly, if the digit received at the selector shown is odd a discriminating signal is transmitted to the succeeding switching stage while if the digit is even no such signal is transmitted or vice versa.

The operations of the circuits shown will now be described in detail, assuming first that no discriminating signal is received. The selector tests free by reason of battery potential over resistance YA, contacts ON1, wiper M3 and contacts MN1 on the incoming test wiper p. When the selector is taken into use relay A operates over its left hand winding and the negative wire to earth connected to this wire at the preceding switch. At contact a1 the circuit of relay B is closed. Relay B operates and at contact b1 earths the incoming test wire to mark the selector engaged. Contact b5 closes a circuit over contacts DON1 and the upper (high resistance) winding of relay C which thereupon operates. Contacts c5 and c6 open the test circuit and contact c7 closes a point in a circuit over the lower (low resistance) winding of relay C for the holding of that relay during impulsion. When impulses are received they are repeated at contact a1 over contacts h8 and c1, lower winding of relay C, contact b6 to magnet DM and the digit

switch is stepped in accordance with the impulses received. Relay C is held in this circuit during impulse reception. When the digit switch is stepped from its normal position the off-normal contacts are operated. Contact DON1 opens the operating circuit for relay C over its upper winding and contact DON2 prepares a self-stepping circuit for the digit switch for homing it. At the end of the impulse train relay C releases and at contact c5 closes a circuit for magnet MU and at contact c6 connects earth to the contacts of the group in the marking bank of the selector corresponding to the received impulses. Contact c3 connects the test relay T over contacts b3 and ws3 to the test wiper P and contact c7 opens a further point in the circuit for magnet DM over the lower winding of relay C. Magnet MU operates in a circuit from earth over contacts b5, DON1, c5, t1, h1, the magnet winding to battery and the wipers of the selector are rotated in search of a free outlet in the group marked in accordance with the received digit. Contact ON1 disconnects the battery from wire p while the selector is off-normal and contacts ON2 maintain the circuit for magnet MU independent of relay C. If the subgroup is connected in the W or Y portions of the bank the marking will be applied over wiper M1, while if it is connected in the X or Z portions of the bank the marking will be applied over wiper M2. Furthermore, if the group in which search is to be made is connected in the Y or Z portions of the bank a connection will be provided for relay WS, over wiper M3 for the Y portion, and over wiper M4 for the Z portion. As for the moment consideration is only being given to the operation for selection in the W and Y portions of the bank the marking will be applied over wiper M1 and if search is to be made in the Y portion relay WS will be operated in a circuit from earth over contact b1, MN1, wiper M3, the right-hand winding of the relay to battery. When the selector wipers are rotated on to contacts in the wanted outlet group earth over contacts c6 wiper M1 and marking wipers G1 or G2 as the case may be, contact ws4 and rectifier MRA will be extended to the right hand winding of relay T and when a free outlet in the group is encountered, denoted by the presence of battery potential on the test wire, relay T will operate over the above traced circuit from earth and over its left-hand winding and contacts c3, b3, ws3 wiper P to the battery potential on the test wire. Contact t1 at its back contacts opens the operating circuit for magnet MU and removes a short circuit from relay H, and at its front contact short-circuits the right hand winding of relay T and earths the test wiper over the low resistance left-hand winding of relay T to engage the outlet. Relay H operates from earth over contacts ON2, c4, b4 and the winding of magnet MU. The magnet will not hold in series with relay H and the rotation of the switch wipers is stopped with the wipers on the contacts of the free outlet. Contact h1 opens a further point in the operating circuit for magnet MU, contacts h2, h3, h4 and h5 switch through the speaking and test wires and contact h6 opens a further point in the circuit for magnet DM. The extension of earth over wire p and contacts h4 and h5 short circuits relay T which thereupon releases. At contact h2 relay A is released and by the falling back of contact a1 relay B releases. Relay H remains held to earth on the test wire applied in the

succeeding switch consequent on the operation of the release relay therein. Contact b3 disconnects the circuit for relay T, contact b4 opens to leave relay H dependent on the earth fed back over the test wire, contact b5 opens in the operating circuit for relay C and contact b6 closes in the homing circuit for the digit switch. If no discriminating signal is to be transmitted from the selector the contact in the bank of wiper M7 corresponding to the impulses received will be connected over contact c1 to the positive speaking wire and at the time the succeeding selector is taken into use the impulse receiving relay therein will operate over a preceding loop to earth over the positive wire, contact c1, wiper M7 and contact b2. The wiper switching relay in the succeeding switch will be shunted by this connection and will not operate. If, however, a discriminating signal is to be transmitted there will be no connection to contact c1 from the bank of wiper M7 and relay WS in the succeeding switch will be included in the loop circuit over which the impulse relay operates. The release of relay B will disconnect the shunting earth, if it has been applied, by which time the succeeding selector will have moved off-normal with the consequence to be described later.

It will now be assumed that at the time the selector shown in the drawing is taken into use a discriminating signal is received and relay WS is operated in the manner above described. The early closure of contact ws5 closes a circuit over contacts c5, t1, and h1 for magnet MU and the selector is set in motion. As soon as the selector wipers move from their normal position contacts ON1 and ON2 are operated and the latter close a circuit for magnet MU that is independent of contacts ws5 and c5. In the meantime relay A has operated and operated relay B and a circuit has been closed over the upper winding of relay C, but by this time the selector has moved off normal and the circuit for magnet MU rendered independent of relay C. Contact b2 on closure short circuits relay WS to release it. When relay C operates relay T is connected over contact c3 to battery over resistance YA and the selector will continue in operation, contact c6 being open, until the wipers have made a traverse of the W and Y portions of the bank. When wipers G1 and G2 reach the first contacts in the X and Z portions of the marking bank a circuit for relay T will be provided over an earth connection to these contacts and the selector will be brought to rest. The release lag of relay C is arranged to cover the period required for this rotation of the selector wipers, even if only one impulse has been received in the selecting digit, so that at the time of operation of relay T contact c4 will be open and relay H will not be operated. In this position of the selector wipers contacts MN1 and MN2 are operated. After the end of the impulse train relay C will release and by this time relay WS will have been released. Contact c3 will open the circuit for relay T, releasing it, and with contact c5 closed magnet MU will again operate and the selector wipers will be driven over the X and Z portions of the bank. When the contacts of the outlet group marked over wiper M2, since the X and Z portions of the bank are concerned this time, are encountered the circuit for the test relay is connected up and the individual outlets of the group are tested over wiper P in the manner before described and when a free outlet is met relays T and H are op-

erated with similar results to those already described.

The operations hitherto described are appropriate to selection in the W and X portions of the bank. If selection is to be made in the Y or Z portions the impulses received by the digit switch will be such that wiper M3 or M4 as the case may be will be connected to relay WS and on the coming to rest of the digit switch at the end of the impulse train relay WS will be operated and by means of its contacts ws1—ws4 the connection to the selector wipers will be changed over from the W and X wipers to the Y and Z wipers. The closure of contact ws5 at this time will be without useful effect.

If, during the search for a free outlet none is encountered in the marked outlet group the selector wipers continue to advance until the last contacts in that portion of the bank in which search is being conducted are reached. These contacts in both portions of the banks of wipers G1 and G2 are connected directly to contact c6 and thence to earth to provide an operating circuit for relay T, and thus a stopping circuit for the selector in that position, the circuit being completed over the appropriate test wiper P and the shunted upper winding of relay C. Relay C operates in series with the test relay after its delay period during which relay H is operated.

At contacts c2 and h6 a source of busy tone is connected over the right hand winding of relay A and by induction into the middle winding is transferred over the last contacts in the several portions of the bank and wipers to the caller's line, the return path being over the negative wiper and the left-hand winding of relay A. At the same time intermittent battery and earth are applied over the middle winding of relay A to give a flashing signal in known manner. During the period when battery is connected to all the windings of relay A the relay is held over its right hand winding and contacts h6 and c2 to earth in the tone circuit. Earth on wire p over contacts h4, b4, c4, h1, MN2, and one of the wipers M5 and M6 operates an overflow meter.

When the caller clears at the end of a conversation or on receipt of busy tone earth is disconnected from the test wire, either at the circuit from which the connection is held or by the release of relay A in an interval during which earth is connected over its middle winding followed by release of relay B. Relay H releases and recloses the circuit for magnet MU at contact h1 and the selector wipers are driven to their home position in which they are stopped by the de-energization of magnet MU on the opening of contacts ON2. Closure of contact h8 completes a homing circuit for the digit switch over contacts a1, DON2, dm and b6 and the digit switch is restored to normal. With the digit switch and the selecting switch both at normal battery is again connected over resistance YA to wire p to enable the selector to be taken into use for another call. Relay WS, if operated, is released with relay H.

What I claim as new and desire to secure by Letters Patent is:

1. In an automatic telephone system, a single motion selector, a plurality of groups of outlets, a marker operated on a straight decimal basis responsive to a train of dial impulses to control the operation of said selector, a transfer relay operated during the said train of impulses and released after the completion thereof, means including said marker for starting said selector in

a searching movement following such release to select any desired one of said outlet groups and an idle outlet therein, means independent of said marker for starting said selector at times in a preliminary movement prior to such release, and means for controlling the extent of each of said movements dependent on the condition of operation of said relay during such movement.

2. In an automatic telephone system, a rotary type selector, a first and a second main group of outlets each comprising more than ten outlets, first and second starting positions for said selector, means to initiate a preliminary operation of said selector upon the seizure thereof in case it is desired to select an outlet in said second group of outlets, a marker having ten marking positions, means for operating said marker to any one of said marking positions in response to a train of impulses to cause said selector to hunt an idle outlet in either of said groups of outlets depending on its starting position, a transfer relay, means for operating said relay during the said preliminary operation and releasing it prior to the said outlet hunting operation, a stopping circuit prepared by said relay in its operated condition for stopping the preliminary operation of said selector when said second starting position is reached, and a second stopping circuit prepared by said relay in its released condition for stopping the outlet hunting operation of said selector when an idle outlet is reached in the selected group of outlets.

3. In an automatic telephone system, a single motion selector, first and second main groups of outlets accessible to said selector, sub-groups in each of said main groups, first and second starting positions for said selector, means responsive to a single train of dial impulses for causing said selector to select a desired sub-group of outlets in either of said main groups depending on the starting position of said selector, said selector then acting automatically to select an idle outlet in said selected sub-group, a pair of line conductors incoming to said selector, a selector line relay connected to one of said conductors, a selector starting-position relay connected to the other of said conductors, means for operating both of said relays in series over said line conductors upon seizure of the selector whenever it is desired to select an outlet in said second group of outlets, and means operated in response to such operation of said starting-position and line relays for driving said selector to said second starting position.

4. In a rotary type selector for use in an automatic telephone system, a set of contact banks and wipers, first and second main groups of outlets connected to said contact banks, sub-groups in each of said main groups, first and second starting positions for said wipers, a marker operated responsive to a single dialled digit for causing said selector to select any of said sub-groups and an idle outlet therein in either of said main groups of outlets depending on the starting position of said wipers, a second set of contact banks and wipers, other outlet groups similarly connected to said second set of contact banks, a wiper switching relay, contacts on said relay for selecting either of said wiper sets, said relay being operated momentarily upon seizure of the selector in case the wanted group is in a second main group of outlets, means operated in response to such preliminary operation of said relay to cause the wipers to advance to their second starting position, and means for operating

and holding said relay in response to the dialled group selecting digit to select said second set of wipers in case the wanted outlet group is connected to said second set of contact banks.

5. In a telephone system, a rotary type selector, contact banks for said selector, a first and a second main group of outlets, sub-groups in each of said main groups, a marker, said marker being set in response to a dialled digit to mark a sub-group in each of said main groups for selection, a transfer relay operated during the setting of said marker and released after such setting to cause said selector to select one of said marked sub-groups and an idle outlet therein, a marking bank for said switch for marking said sub-groups for selection in accordance with the setting of said marker, a first and a second starting position for said selector, a first and a second start contact for said marking bank, a permanent marking for said second start contact in said marking bank, means for causing said selector to advance in a preliminary movement upon seizure in case it is desired to select a sub-group in said second group of outlets, means for operating said transfer relay also during said preliminary movement, and a stopping circuit including said permanently marked second start contact and front contacts on said operated transfer relay for arresting said preliminary movement and stopping said selector in its second starting position.

6. In an automatic telephone system, a rotary type selector switch, contact banks and wipers for said switch, two main groups of outlets connected to said banks, sub-groups of outlets in each of said main groups, first and second starting positions for said wipers, a pair of speech conductors incoming to said switch, a pulsing relay normally connected to one of said conductors, a discriminating relay normally connected to the other of said conductors, means for momentarily operating said discriminating relay in series with said pulsing relay upon seizure of said selector to advance said wipers away from their first starting position in case it is desired to select a sub-group of outlets in said second main group, off-normal contacts on said switch for maintaining said advance independently of said discriminating relay, a stopping relay for said switch, back contacts on said stopping relay in series with said off-normal contacts, means for operating said stopping relay and opening said back contacts to stop said advance and said wipers in said second starting position, and impulse responsive means operated under the control of said pulsing relay in response to a single dialled digit for causing said wipers to select a particular group of outlets in either of said main groups depending on the starting position of said wipers.

7. In a telephone system, a single motion selector switch, wipers for said switch, two main groups of outlets accessible to said wipers, a normal and a second starting position for said wipers, means for causing said wipers to select an idle outlet in either of said main groups of outlets depending on the starting position of said wipers, a pair of conductors incoming to said switch, a relay normally connected to one of said conductors, means for momentarily operating said relay upon seizure of said switch whenever the second group of outlets is wanted, a start circuit completed responsive to said relay opera-

tion for advancing said wipers away from their normal starting position, off-normal contacts operated when said wipers leave said normal starting position for continuing said advance independently of said start circuit, means for stopping said wipers automatically at said second starting position, and front and back contacts reversed by said switch in each of said normal and second starting positions to cause different operations upon the completion of the selection of an idle outlet, depending on which of said main groups of outlets is involved in said selection.

8. In an automatic telephone system, a rotary type selector, a first and a second set of wipers for said selector, a first and a second main group of outlets respectively accessible to each of said sets of wipers, sub-groups in each of said main groups, a normal and a second starting position for said wipers, a marker switch for said selector operated by dial pulses, means for causing the wipers of said selector to select an idle outlet in one of said sub-groups in either of said main groups depending on the starting position of said wipers and the operated position of said marker switch, a wiper switching relay, means for causing a preliminary operation of said relay upon seizure of said selector, means operated responsive to the said preliminary operation to advance said selector from its normal to its second starting position, a pair of wiper-switching contact banks for said marker switch, midnormal contacts reversed by said selector in its second starting position, means for again operating said wiper switching relay through either of said wiper-switching contact banks depending on the position of said midnormal contacts in case it is desired to select an outlet accessible only to said second set of selector wipers, and contacts operated by said wiper switching relay to cause such selection to occur through said second set of selector wipers.

9. In an automatic telephone system, a rotary type selector, speech conductors incoming to said selector, a first and a second rank of bank contacts for said selector and a first and a second main group of outlets connected respectively thereto, sub-groups in each of said main groups, a normal and a second starting position for said selector; a marker switch operated responsive to a dialled digit to cause said selector to select an idle outlet in either of said main groups and, depending on the digit dialled, in any one of the sub-groups therein; discriminating means operated upon seizure of said selector for causing said selector to advance from its normal starting position to its second starting position preliminary to its outlet selecting operation in case the desired outlet is in said second main group of outlets, a transfer relay operated during the dial pulses and released at their conclusion to initiate the outlet selecting operation, a switching relay operated upon the selection of an idle outlet to extend said speech conductors to such selected outlet, means for advancing said selector to the last contact of the rank of contacts over which it is searching in case no idle outlet is available in the selected sub-group, and means for operating said switching relay and re-operating said transfer relay when the said last contact is reached for passing a busy signal back over said incoming speech conductors.
